UNITED STATES PATENT OFFICE

171,084

SET OF EDUCATIONAL ALPHABET CARDS

Miriam Elizabeth Corbett and Gladys C. Hoff,
Richmond, Ind.

Application May 12, 1950, Serial No. 9,889

Term of patent 3½ years

(Cl. D25—1)

To all whom it may concern:

Be it known that we, Miriam Elizabeth Corbett and Gladys C. Hoff, both citizens of the United States, and both residing at Richmond, in the county of Wayne and State of Indiana, have invented a new, original, and ornamental Design for a Set of Educational Alphabet Cards, of which the following is a specification, reference being had to the accompanying drawings, forming a part hereof.

Figures 1 through 26 show front views of one complete alphabet unit of the set of educational alphabet cards;

Figures 27 and 28 show front views of two of a second alphabet unit;

Figures 29 and 30 show front views of two of another alphabet unit;

Figures 31 and 32 show front views of two of another alphabet unit;

Figures 33 and 34 show front views of two of another alphabet unit;

Figures 35 through 39 show front views of a vowel card unit;

Figure 40 shows the appearance of the back of each card.

A complete set of 155 cards consists of 5 complete alphabet units and 5 complete vowel units,

the whole showing our new design. Each unit is colored differently from the other units and the vowel units are colored differently from the alphabet units.

We claim:

The ornamental design for a set of educational alphabet cards, substantially as shown and described.

MIRIAM ELIZABETH CORBETT,
GLADYS C. HOFF.
